HOT-GAS PISTON ENGINE COMPRISING ONE
OR MORE CLOSED CYCLES

Alexandre Horowitz and Cornelis Herman Buitenhuis, Eindhoven, Netherlands, assignors to Hartford National Bank and Trust Company, Hartford, Conn., as trustee

Application August 13, 1948, Serial No. 44,146
In the Netherlands September 13, 1947

4 Claims. (Cl. 60—24)

1

This invention relates to engines comprising four cylinders and pistons movable therein, which cylinders are provided on two centre lines, enclosing an angle of 90°, so as to be grouped about the shaft of the engine, the pistons which are movable in the cylinders provided on the same centre line being rigidly coupled together, and the movements of the pistons being determined by a body which is rotatable about an eccentric seated on the shaft of the engine, said body exhibiting a sectional area which is substantially rectangular in a plane normal to the shaft of the engine.

According to the invention, such an engine is constructed as a hot-gas piston engine comprising closed cycles, each of the cycles being performed in two cylinders provided on different centre lines, the cylinders which are provided on the same centre line comprising solely cold spaces or solely hot spaces, and the heater, regenerator and cooler associated with a determined cycle jointly surrounding either of the two cylinders associated with the cycle concerned.

The term "hot-gas piston engines" is understood in this case to mean more particularly a hot-gas engine or a refrigerator operating on the reversed hot-gas piston principle.

The engine according to the invention exhibits the advantage that it permits of being constructed in a very compact manner, since transmission members, such as piston rods, driving rods and the like are dispensed with. From this ensues the important advantage that the cold and hot pistons associated with a cycle may be arranged to be very close to one another, so that the length of the communication channel between the cylinders in which the pistons move and, consequently, the clearance space may be small, which greatly influences the specific power of the engine. In general, a compact construction of a hot-gas piston engine can be realised only with difficulty. From the thermal point of view, it is inconvenient if the cold space is liable to be exposed to the influence, even small, of the hot parts of the engine. It is then often compulsory, in order to minimise this influence, to find a compromise by which the communication ducts between the hot and cold spaces and, hence, the clearance space become larger than is required or desired. In the engine according to the invention it is possible greatly to reduce the influence exerted by the heat of the hot parts upon the cold space, whilst nevertheless the clearance space remains small.

In one embodiment of the invention, the cyl-

2

inders comprising a cold space have a dimension, as measured in the direction of the centre line, which is smaller than that of the cylinders comprising a hot space, the star shape of the engine then changing to a rectangular shape. This rectangle has two long and two short sides and here one of the advantages of the invention, viz. the concentrated, compact structure of the engine, becomes greatly manifest. Furthermore the communication ducts are very short, since the cold spaces are located adjacent the coolers.

In a further embodiment of the invention, the engine is preferably constructed to be such that the ratio between the stroke of a piston and the diameter of the cylinder in which the piston moves is comprised between 0.3 and 0.4. Owing to this comparatively small ratio, as a result of which the stroke is small with respect to the diameter of the cylinder, important advantages are obtained, viz. the engine is even more compact in construction, occupies an even smaller space than the body eccentrically arranged on the main shaft already permitted and, in addition, the engine is capable of being dismounted in a simple and rapid manner.

The invention will now be described more fully with reference to the accompanying drawing, the figures of which are to be regarded as embodiments thereof, given by way of example.

30 Fig. 1 shows diagrammatically a hot-gas piston engine according to the invention.

Fig. 2 is a sectional view taken on the line II—II of the engine shown in Fig. 1.

Referring to Figs. 1 and 2, reference numeral 35 101 designates an engine housing, with which two cylindrical bodies 102 and 103 are joined. These cylindrical bodies contain two other cylindrical bodies 104 and 105 so as to form between them an annular channel comprising the heat-transfer elements of heaters 106 and 107 and of coolers 108 and 109. Elements 134 close off one end of the annular channels in known manner. Regenerators 110 and 111 are provided between the two heaters and coolers. In the cylinders 104 and 105 can move two piston-shaped bodies 112 and 113, which are connected by coupling bodies 114 and 115. At right angles to the centre line of the cylinders 104 and 105 are two further cylinders 116 and 117 in which 40 piston-shaped bodies 118 and 119 are movable. The two piston-shaped bodies 118 and 119 are interconnected by coupling bodies 120 and 121, so that these pistons also perform, to a certain extent, a constrained movement. The spaces 45 50 above the pistons 118 and 119 communicate

through ducts 122 and 123 with the spaces above the pistons 113 and 112. The volume of one of the cycles provided is thus determined by the surfaces of the hot piston 113 and the cold piston 118 and the volume of the other cycle is accordingly determined by the surfaces of the hot piston 112 and the cold piston 119. Since the two piston surfaces determining the volume of the cycle exhibit a phase difference of 90°, the cold piston then having the lead in the sense of rotation shown, the engine will operate as a hot-gas engine. Four surfaces 124, 125, 126 and 127 are provided on the four pistons 112, 113, 118 and 119. On the main shaft 128 of the engine is seated an eccentric 129, which is adapted to rotate in a body 130 of rectangular sectional area. The eccentric 129 is rigidly secured to the shaft 128, whereas the body 130 is adapted to rotate freely about the eccentric 129. Needle bearings are provided between the surfaces 124, 125, 126, 127 and the corresponding sides of the rectangular body 130, so that only rolling friction can occur between the corresponding surfaces. The ratio between the stroke of the pistons and the diameter of the cylinders in which the pistons move, is 0.35 so that the pistons and hence the body 130 need only perform comparatively small motions, whilst the engine is nevertheless capable of developing a comparatively high power.

The hot-gas engine described, which is an example of the invention, may be very compact in construction, so that an engine of a determined power will, as a rule, occupy a smaller space than other similar engines. Moreover, the mechanical losses are reduced to a minimum. If a further bearing with rolling friction is provided between the rectangular body 130 and the eccentric 129, which is possible without the need for further means, there is only rolling friction in the engine with the exception of the friction of the piston rings 133 against the wall of the cylinder, which is, in the engines according to the invention, generally smaller than with the use of driving rods. From a thermal viewpoint it is particularly advantageous that the coolers surround the hot cylinders and that the cold pistons are comparatively far remote from the hot part of the engine, whilst nevertheless the communication ducts 122 and 123 are as short as possible, so that the inevitable clearance space is very small. The housing of the engine can also remain cool without the need for further means. Dismounting of the engine concerned for inspection or the like may be simple. After removal of a lid 131, the bolts 132 connecting at one side the connecting pieces 114 and 115 to the piston 112 may be loosened, whereupon after removal of lids on the cylinders 102 and 103 the two pistons 112 and 113 may be taken out of the engine. The pistons 118 and 119 may be removed in a similar manner. Since the gas pressures are invariably directed towards the centre of the engine, the connecting pieces 120, 121, 114 and 115 are invariably subject to pressure. Since the connecting pieces are slightly resilient, troublesome play is prevented even after some wear and tear of the pressure surfaces.

What we claim is:

1. A hot-gas piston engine comprising four cylinders each having a movable piston therein, a drive shaft for said engine, said cylinders being arranged around said drive shaft in two pairs, one of said two pairs being arranged on a center line which intersects substantially perpendicu-

larly with the center line of the other pair, both of said center lines in turn intersecting the center line of said shaft substantially perpendicularly thereto, said cylinders of each of said pairs being located on opposite sides of said shaft, respectively, said pistons in said cylinders which are opposite each other on the same center line being rigidly coupled to one another, an eccentric mounted on said shaft, a body surrounding said eccentric, said eccentric being rotatable in said body, said body having a sectional area which is substantially rectangular in a plane normal to said shaft, said pistons comprising means for imparting their movement to said body, both cylinders of one of said pairs each comprising a separate hot space, both cylinders of the other of said pairs each comprising a separate cold space, conduit means communicating one cylinder of one of said pairs with one cylinder of the other of said pairs, and a heater, regenerator and cooler operatively associated with each communicating pair of cylinders.

2. A hot-gas piston engine comprising four cylinders each having a movable piston therein, a drive shaft for said engine, said cylinders being arranged around said drive shaft in two pairs, one of said two pairs being arranged on a center line which intersects substantially perpendicularly with the center line of the other pair, both of said center lines in turn intersecting the center line of said shaft substantially perpendicularly thereto, said cylinders of each of said pairs being located on opposite sides of said shaft, respectively, said pistons in said cylinders which are opposite each other on the same center line being rigidly coupled to one another, an eccentric mounted on said shaft, a body surrounding said eccentric, said eccentric being rotatable in said body, said body having a sectional area which is substantially rectangular in a plane normal to said shaft, said pistons comprising means for imparting their movement to said body, both cylinders of one of said pairs each comprising a separate hot space, both cylinders of the other of said pairs each comprising a separate cold space, said pair of cylinders which comprise said separate hot spaces having a dimension, as measured in the direction of the center line thereof, which is larger than that of said pair of cylinders which comprise said separate cold spaces, conduit means communicating one cylinder of one of said pairs with one cylinder of the other of said pairs, and a heater, regenerator and cooler operatively associated with each communicating pair of cylinders.

3. A hot-gas piston engine comprising four cylinders each having a predetermined diameter and each having a movable piston therein, a drive shaft for said engine, said cylinders being arranged around said drive shaft in two pairs, one of said two pairs being arranged on a center line which intersects substantially perpendicularly with the center line of the other pair, both of said center lines in turn intersecting the center line of said shaft substantially perpendicularly thereto, said cylinders of each of said pairs being located on opposite sides of said shaft, respectively, said pistons in said cylinders which are opposite each other on the same center line being rigidly coupled to one another, an eccentric mounted on said shaft, a body surrounding said eccentric, said eccentric being rotatable in said body, said body having a sectional area which is substantially rectangular in a plane normal

to said shaft, said pistons comprising means for imparting their movement to said body, the ratio between the stroke of each of said pistons and of the diameter of the said cylinder in which the associated one of said pistons moves, being between 0.3 and 0.4, both cylinders of one of said pairs thereof each comprising a separate hot space, both cylinders of the other of said pairs each comprising a separate cold space, conduit means communicating one cylinder of one of said pairs with one cylinder of the other of said pairs, and a heater, regenerator and cooler operatively associated with each communicating pair of cylinders.

4. A hot-gas piston engine comprising four cylinders each having a predetermined diameter and each having a movable piston therein, a drive shaft for said engine, said cylinders being arranged around said drive shaft in two pairs, one of said two pairs being arranged on a center line which intersects substantially perpendicularly with the center line of the other pair, both of said center lines in turn intersecting the center line of said shaft substantially perpendicularly thereto, said cylinders of each of said pairs being located on opposite sides of said shaft, respectively, said pistons in said cylinders which are opposite each other on the same center line being

rigidly coupled to one another, an eccentric mounted on said shaft, a body surrounding said eccentric, said eccentric being rotatable in said body, said body having a sectional area which is substantially rectangular in a plane normal to said shaft, said pistons comprising means for imparting their movement to said body, the ratio between the stroke of each of said pistons and of the diameter of the said cylinder in which the associated one of said pistons moves, being between 0.3 and 0.4, both cylinders of one of said pairs thereof each comprising a separate hot space, both cylinders of the other of said pairs each comprising a separate cold space, said pair of cylinders which comprise said separate hot spaces having a dimension, as measured in the direction of the center line thereof, which is larger than that of said pair of cylinders which comprise said separate cold spaces, conduit means communicating one cylinder of one of said pairs with one cylinder of the other of said pairs, and a heater, regenerator and cooler operatively associated with each communicating pair of cylinders.
